UNITED STATES PATENT OFFICE.

OTTO ROTHENSTEIN, OF CHICAGO, ILLINOIS.

METHOD AND APPARATUS FOR CONTROLLING ELECTRIC CIRCUITS.

No. 895,044

Specification of Letters Patent.

Patented Aug. 4, 1908.

Application filed November 1, 1906. Serial No. 341,576.

To all whom it may concern:

Be it known that I, OTTO ROTHENSTEIN, a citizen of the United States, and a resident of Chicago, in the county of Cook and State 5 of Illinois, have invented certain new and useful Improvements in Methods and Apparatus for Controlling Electric Circuits, of which the following is a specification.

This invention relates to a method and apparatus for controlling electric circuits in which a conducting liquid—as per instance mercury—is used to make and break the circuit, both operations taking place below the level of an inert non conducting fluid, as per 15 instance petroleum.

Figure 1 is a horizontal section, taken on the line S—S Fig. 2, looking downwards. Fig. 2 is a sectional elevation taken on the line E—E of Fig. 1.

20 The receptacle 3, preferably made of cast iron, is filled in its lower conical part with a conducting liquid 52, preferably mercury, the non conducting inert fluid—petroleum or alcohol—filling the other part of the receptacle 3, as shown in the drawing. The cover 4 is held in place by four screws 16, and the registering pin 17. Cast in one piece with the cover 4 is the barrel 5 extending nearly to the bottom of receptacle 3. The 25 barrel 5 is closed at its top by the flanged piece 6 containing the bearing 7. The vertical shaft 8 passes through this bearing 7 and has on its lower end the elevating screw 9, approximately midway the feather key 10, 30 on its upper end the insulating coupling 11, which connects the shaft to the electric motor 12, the frame of said motor being supported by the insulating distance piece 13. Immediately below the bearing 7 are located 35 the packing ring 14, preferably fiber, and a steel collar 15, held in place by the set screw 18. Above the bearing is placed the fiber washer 19. The bearing 7 is provided with the lubricating channel 20, and the oil groove 40 21. The hollow trunk piston 22 is adjusted for a running or sliding fit over the shaft 8 and the feather-key 10, and into the barrel 5. The hollow trunk piston 22 is further provided with a number of small grooves, 23, 45 24 for the purpose of packing by means of the capillary action of the liquid, 24 is the ball raceway into which fit the balls 25, said balls being also supported by the screws 26 with their jam nuts 27. The access for the 50 screws 26 and the balls 25 into the raceway 24 of the piston 22 is made possible by the

longitudinal slots 28 of the barrel 5. The screws 26 with their jam nuts 27 are carried in the threaded ends of the forks 29. The position of this fork 29 is controlled by the 55 adjusting screw 30 with its jam nut 32. Said screw 30 being secured to the fork 29 by the tangential pin 31, which fits into a groove of the adjusting screw 30. The barrel 5 is provided with the nozzle 33. Opposite to it the anvil 34 is secured to the cover 4 by means of the screw 35, the insulating bushing 36 and the nuts 58 which also serve as one terminal post. The receptacle 3 rests on a sub-base 37 and is held in place by four 60 set screws 38, which bear upon the conical surface of the rim 39. The receptacle 3 also has three radical extensions 40 which serve the double purpose of supporting said receptacle when it is handled without the sub-base 75 37, and facilitating machining during the process of manufacture.

The condenser 46, frequently used with this class of apparatus and consisting of alternate layers of tin-foil and insulating material is placed between the insulating pieces 42 and 43, and is pressed against the abutment 41 of the sub-base 37 by means of the screws 44 and 45. The last named screw carries the terminal post 49. One terminal 80 of the condenser 46 is attached to this screw. Thus electric connection is established with the sub-base 37 and through the set screws 38, with the metallic receptacle 3 and the mercury 52 contained therein. The other 85 three screws 44 are preferably flat headed, but all four screws are provided with washers 47 and nuts 48. The second terminal of the condenser 46 is formed by the insulated wire 50, which passes through the insulating bushing 51 to the terminal 58. The hollow piston 22, as clearly shown in the drawing has parts of its wall cut away leaving thus openings, preferably of triangular shape. For the sake of convenience and clearness the apparatus shown and described here has a piston 90 with two such openings.

The apparatus works in the following manner: The shaft 8 is rotated by means of the motor 12. The elevating screw 9 raises the 10 mercury into the hollow piston 22. As long as an opening of the piston 22 is in line with the nozzle 33 a stream of mercury is thrown against the anvil 34, thus closing the electric circuit. This stream of the conducting liquid ceases immediately as soon as the nozzle 38 is covered by the wall of the piston 22, and

the mass of mercury which forms the connecting stream between nozzle 33 and anvil 34 falls quickly to the bottom of the receptacle 3. As this whole process takes place 5 below the level of the non conducting inert fluid, arcing is prevented effectively. The openings of the piston 22 vary in width throughout their length and the position of the piston in relation to the nozzle 33 is controlled by the balls 25, the screws 26, the fork 29 and the adjusting screw 30, it follows 10 that the duration of contact and interruption can be controlled from without, by merely turning the adjusting screw 30.

15 The advantages of my invention are numerous and will be appreciated by those skilled in the art. Some of these advantages are:—the freedom from explosions, there being no large bodies revolving within the oil to 20 create spaces in which accumulated gases could be ignited; the contact is broken at two points, and the mercury sinks to the bottom quickly without sputtering and with very little carbonization of the oil. The stream 25 of mercury is entirely suppressed during the interval of interruption, and the mercury is not uselessly dispersed into small globules during this interval, and the "emulsification" of the mercury, (heavily accelerated 30 by such dispersion), is counteracted in a most economical and efficient manner. The amount of motive power consumed is very small, there being no large or unbalanced masses to set in motion. The period of contact and that of interruption can be quickly 35 and exactly varied during the operation of the device, so that the best conditions of working may be obtained in any particular case.

40 The device can be used to break alternating currents in such a manner that one-half of the wave may be entirely suppressed, the distortions of the wave-form of the current due to changes of self-induction and capacity 45 being readily corrected. It can also be used in various other ways, and for various purposes, by varying the number or arrangement of the nozzles and anvils. In fact, various changes can be made in the construction 50 and arrangement of the parts by those skilled in the art, without departing from the spirit and scope of my invention as defined in the appended claims.

1. The method of controlling electric circuits by directing a stream of conducting liquid through an inert insulating liquid, towards another fixed terminal submerged in said inert insulating fluid for the purpose of closing the circuit, and suppressing said stream of conducting liquid altogether, for the purpose of interrupting the electric circuit.

2. The method of controlling electric circuits by directing a stream of conducting liquid through an inert insulating fluid to-

wards another fixed terminal submerged in said inert insulating fluid for the purpose of closing the circuit, suppressing said stream of conducting liquid altogether for the purpose of interrupting the circuit, and varying the period of time during which said conducting stream lasts or ceases, thereby controlling the character of the current impulses.

3. In an electric current controller: a receptacle, a conducting liquid, an inert fluid, means to raise the level or the pressure of the conducting liquid within a space reserved for such purpose, means to direct a stream of the conducting liquid towards a fixed insulated point immersed in said inert fluid, through said inert fluid, and means to suppress the stream of the conducting liquid during the time of current interruption and for the purpose of interrupting the circuit.

4. In an electric current controller: a receptacle, a conducting liquid, an inert insulating fluid, means for raising the conducting liquid within a space reserved for such purpose, means to direct a stream of the conducting liquid through the inert fluid, towards an insulated point, submerged in said inert fluid, at the time, and for the purpose of, establishing the circuit, means to suppress the flow of the conducting liquid, at the time, and for the purpose of, interrupting the circuit, and means to vary the respective periods during which the stream of conducting liquid lasts or ceases.

5. In an electric current controller: a receptacle containing a conducting liquid of comparatively high specific gravity, an inert insulating fluid of comparatively low specific gravity, a pressure chamber suspended therein, means to admit the conducting liquid into said chamber, an elevating device within said pressure chamber, an aperture in said pressure chamber, adapted to permit the exit of the conducting liquid from said pressure chamber through the inert insulating fluid towards a contact point submerged in said inert insulating fluid, for the purpose of establishing an electric circuit, means to cutoff temporarily the pressure or the supply of conducting liquid from the aperture of said pressure chamber, thus stopping the flow of conducting fluid for the purpose of interrupting the electric circuit.

6. In an electric current controller: a receptacle containing a conducting liquid of comparatively high specific gravity, an inert non conducting fluid of comparatively low specific gravity, a pressure chamber suspended therein, means to admit the conducting liquid into said pressure chamber continuously, an elevating device within said chamber, an aperture in said pressure chamber adapted to permit the exit of the conducting liquid from said pressure chamber through the inert non conducting fluid towards a co-

tact point submerged in said insulating inert fluid, for the purpose and at the time of closing an electric circuit or circuits, means to cut off temporarily the pressure or the supply of conducting liquid from the aperture in said pressure chamber, thus stopping the exit at the time and for the purpose of interrupting the circuit, and means to vary the period of flow as well as the period of cut off.

10 7. In an electric circuit controller: a receptacle containing a conducting liquid of comparatively high specific gravity, a non conducting fluid of comparatively low specific gravity, a cover fitting said receptacle containing in its center part a barrel extending closely to the bottom of said receptacle, said barrel having an opening on the bottom to admit the conducting fluid, a journal fitting the upper part of said barrel, adapted to receive a rotating shaft provided with a keyway and an elevating screw on its bottom, a hollow piston fitting slidingly over said shaft and into said barrel, an aperture in said barrel and said piston, the whole aforesaid structure forming one terminal of an electric circuit: an insulated contact point within the receptacle but without the barrel and in juxtaposition with the aperture in the barrel, forming the second terminal of an electric circuit, said aperture in barrel and said contact point being below the level of the non conducting but above the level of the conducting fluid, and means to rotate said shaft, piston and elevating screw simultaneously thereby directing a stream of conducting liquid from said barrel towards said submerged contact point for the purpose of closing the circuit as long as apertures in said barrel and piston coincide, and stopping the flow of said conducting liquid for the pur-

pose of interrupting the electric circuit when said aperture in said barrel and said piston are not in juxtaposition.

8. In an electric circuit controller: a receptacle containing a conducting liquid of comparatively high specific gravity, a non conducting inert fluid of comparatively low specific gravity, a cover fitting closely said receptacle having from its center part extending a barrel nearly to the bottom of said receptacle, admitting thus the conducting liquid into said barrel: a journal fitting the upper part of said barrel, adapted to receive a rotating shaft provided with a feather key and an elevating screw on its lower end; a hollow piston fitting slidingly over said shaft and key and into said barrel; an aperture of comparatively small area in said barrel, apertures varying in width throughout their length in the walls of the piston; the whole aforesaid structure forming one terminal of an electric circuit; an insulated contact point within the receptacle but without the barrel and submerged in the non conducting insulating fluid in juxtaposition with the aperture in the barrel, forming the second terminal of an electric circuit, means to rotate said shaft, piston and elevating screw simultaneously, in the manner and for the purpose described, and means to vary the position of said piston and thereby the relative width of apertures in said piston in reference to the aperture in said barrel, in the manner and for the purpose described above.

In testimony whereof, I have hereunto set my hand.

OTTO ROTHENSTEIN.
